CLAIM

The ornamental design for a medical connector, as shown and described.

DESCRIPTION

FIG. 1 illustrates a side view of an embodiment of a medical connector, the other side being a mirror image thereof; and, FIG. 2 illustrates a front perspective view of the embodiment of FIG. 1.

The broken lines shown in the figures are included for the purpose of illustrating unclaimed portions of the medical connector and form no part of the claimed design.

1 Claim, 2 Drawing Sheets

Related U.S. Application Data

continuation of application No. 14/199,836, filed on Mar. 6, 2014, now Pat. No. 9,933,094, which is a continuation of application No. PCT/US2012/054289, filed on Sep. 7, 2012.
